UNITED STATES PATENT OFFICE.

FRANK MARION KENNEDY, OF CLARENDON, ARKANSAS.

RUNNING GEAR FOR WAGONS.

Application filed May 12, 1926. Serial No. 103,587.

This invention relates to an improved running gear for wagons, and among the objects of the invention are the elimination of the use of wagon hounds, sway bars and the like; the provision of a flexible joint between the front and rear axle assemblies; the provision of a novel, effective and properly braced mounting for the rocking bolster mounted above the front axle assembly 10 in spaced relation to the front axle assembly or to the sand board in the event a sand board is employed, and the simplification of the fifth wheel arrangement.

A further object is to provide a running gear for wagons having these advantages and which is of simple and durable construction, reliable and efficient in operation and easy and comparatively inexpensive to manufacture.

Other objects and advantages reside in certain novel features of the construction, arrangement and combination of parts which will be hereinafter more fully described and particularly pointed out in the appended 25 claims, reference being had to the accompanying drawings forming a part of this specification, and in which:—

Figure 1 is a view partly in side elevation and partly in section showing the invention 30 embodied in a running gear employing a front axle assembly of special construction,

Figure 2 is a plan view thereof.

Figure 3 is a view similar to Fig. 1 but showing the invention embodied in a running gear employing the ordinary type of 35 axle and sand board;

Figure 4 shows a preferred mode of bracing the yoke;

Figure 5 is a detail view of the shoulder 40 bolt employed in connection with the braces for the bolster;

Figure 6 is a fragmentary detail view in 45 elevation showing a modified form of connection between the yoke and the reach rod, and

Figure 7 illustrates another modified form of this feature.

Referring to the drawings and more particularly to Figures 1 to 4, inclusive, it will 50 be seen that the running gear embodying the present invention comprises in all of the embodiments shown in Figs. 1 to 4 a metal yoke 1 having a body portion 2 and spaced arms 3 extending forwardly of the body portion. This structure is substantially the same throughout Figs. 1 to 4 although this

shape and size of the parts may be somewhat varied. The body portion 2 presents a flat and smooth rear face and abuts a similarly formed face provided on the front of the 60 body portion 4 of a U-shaped bracket, designated generally at 5, and including in addition to the body portion 4 spaced arms 6 which extend rearwardly from the body portion and which are secured by bolts and 65 nuts 7 or other suitable fastening means to a reach rod 8.

Means is provided for pivotally connecting the body portion 2 of the yoke 1 to the body portion 4 of the bracket 5 and this 70 means comprises a pivot bolt 9 having its head 10 engaged with a rectangular washer 11 engaged with the corners defined by the arms and body portion of the yoke. The shank 12 of the pivot bolt extends through 75 the opening of the washer 11 and through aligned pivot openings in the body portions 2 and 4 and also through the opening of the washer 13 similar to the washer 11 and engaged in the corners defined by the body 80 portion 4 and arms 6 of the bracket 5. A nut 14 is threaded on the shank 12 of the bolt 9 and holds the bolt against displacement. The nut 14 may be castellated and secured against displacement by means of the 85 ordinary cotter pin.

The forward ends of the arms 3 of the yoke straddle the front axle assembly and the simplified fifth wheel arrangement.

In the form of the invention shown in 90 Figs. 1 and 2 a special form of axle assembly is illustrated and preferably is of the construction fully shown and described in my prior Patent No. 1,575,064, granted March 2, 1926 and as in the patented construction the 95 axle assembly embodies a flatly disposed beam 15 and a vertically disposed beam 16 which are united to the bases of the axle spindle by means of a tie rod 18 as more clearly set forth in the patent referred to. On the vertically disposed beam 16 a single 100 fifth wheel comprising an annular metal plate 19 is supported, this fifth wheel being braced by means of brace bars 20 fastened to the fifth wheel and to the flatly disposed beam 15.

In the form of the invention shown in 110 Figs. 3 and 4 the axle assembly is of the usual type and includes the usual axle beam 21 to which the axle spindles (not shown) are connected in the usual fashion. On top of the axle beam 21 a sand board 22 is dis-

posed and on this sand board an annular plate 23 constituting the fifth wheel rests, the plate 23 being held in position by brace bars 24 fastened to the plate 23 and to the sand board 22.

In all embodiments of the invention the forward end of the lower arm 3 of the yoke is disposed below the front axle assembly and the upper arm 3 of the yoke engages 10 the annular plate 19 or 23, as the case may be. The portion of the arm 3 which engages the annular plate is enlarged laterally, as at 3^a, since this portion 3^a constitutes the other member of the fifth wheel. In Fig. 4 the 15 forward ends of the arms 3 are strengthened by bending or doubling the material of the arm back upon itself, as indicated at 3^b. On top of the forward end of the upper arm 3 of the yoke a rocking bolster 25 is mounted. 20 The bolster, yoke and front axle assembly are all pivotally connected by means of the usual king bolt 26 extending through aligned bolt holes in the bolster, the arms of the yoke and the elements of the axle assembly. 25

The bolster 25 rests on the forward end 3^a of the upper arm 3 of the yoke 1 and is braced and held in proper position by means of a pair of braces 27 and a V-shaped brace 28. One brace 27 is arranged forwardly of 30 the bolster and the other rearwardly thereof, the upper ends of the two braces 27 being fastened to the bolster by common fastening means, such as bolts and nuts 29. The lower ends of the braces 27 are secured to the upper 35 arm 3^a of the yoke by bolts 30 of special construction. Nuts 31 serve to hold the bolts 30 in position. The arms 32 of the V-shaped brace 28 are secured by bolts and nuts 33 to the bolster, as shown in Fig. 2, and the apex 40 of this V-shaped brace is fastened to the upper arm 3 of the yoke by means of a bolt similar to the bolt 30 and a nut similar to the nut 31. It is usually desirable for the 45 bolster to have a capacity for limited movement relative to the yoke and for this purpose the openings in the braces 27 and 28 through which the bolts 30 pass are slightly larger than the bolts. This permits the bolster to rock with the body of the wagon 50 when the front axle twists relative to the rear axle, the king bolt aperture being sufficiently large for this purpose. It is always desirable for the bolster to remain in substantial parallelism with the rear axle and 55 this capacity is had because of the pivotal connection between the yoke connected with the front axle assembly and the reach and because the braces may move to a slight extent at least relative to the bolts which fasten 60 them to the yoke.

Preferably the yoke is braced as shown in Fig. 4 in order to maintain the body portion 2 against distortion. The rocking bolster and the rod on the wagon has a tendency to lurch forward or backward and spring the

arms of the yoke from the body portion thereof, thereby impairing the connection between the yoke and the reach. The bracing shown in Fig. 4 prevents distortion of the yoke particularly at its body portion and this bracing consists of bolts 40 and 41, the bolt 41 conveniently replacing the bolt 30 which otherwise would be employed between the V-shaped brace 28 and the upper arm 3 of the yoke. The bolts 40 and 41 pass through apertured and offset end portions 42 and 43, respectively, of a brace bar 44 positioned between the arms 3 of the yoke. Sleeves 45 and 46 fit over the shanks of the bolts and engage the ends 42 and 43, respectively, and the lower and upper arms respectively of the yoke. The bolts 40 and 41 are held against displacement by means of nuts 47 and 48. If desired washers 49 and 50 may be interposed between the nuts and the adjacent face of the lower bar 3.

If it is not desirable to employ a pivotal connection between the yoke and the reach rod 8 the bars of the yoke may be merged into each other, as shown in Fig. 6, the bars of the yoke being designated at 60 and 61 and being shown as merging into an attaching bracket 62 bolted, as at 63, to the reach rod 8. The forward ends of the arms of the yoke are connected up with the fifth wheel arrangement, the front axle assembly and the bolster, as in the other forms of the invention. Another modified form of attachment of the yoke to the reach rod is shown in Fig. 7. In Fig. 7 the yoke is replaced by spaced bars 65 and 66 which have their rear ends flatly engaged with the reach rod 8 and which is secured to the reach rod 8 by means of bolts and nuts 67. In this form of the invention the forward end of the reach 105 rod is made to constitute the body portion of the yoke.

I claim:—

1. A running gear for wagons having a metal yoke including a body portion and arms extending forwardly from the body portion, the body portion having a flat rear face of substantial area and a pivotal connection at the rear end of the yoke adapted to pivotally connect the same to the reach rod and comprising a U-shaped bracket having a body portion provided with a flat forward face flatly engaging the rear face of the body portion of the yoke, a pivot bolt and nut for pivotally securing the body portion of the yoke to the body portion of the bracket, the bracket having means whereby it may be secured to the reach rod.

2. A running gear for wagons having a metal yoke including a body portion and arms extending forwardly from the body portion, the body portion having a flat rear face of substantial area and a pivotal connection at the rear end of the yoke adapted to pivotally connect the same to the reach rod.

and comprising a U-shaped bracket having a body portion provided with a flat forward face flatly engaging the rear face of the body portion of the yoke, a pivot bolt and a nut for pivotally securing the body portion of the yoke to the body portion of the bracket, the bracket having means whereby it may be secured to the reach rod, and bracing washers mounted on the pivot bolt and 10 engaging the corners of the bracket and yoke to brace the engaging body portions thereof.

3. A running gear for wagons having a metal yoke including a body portion adapted 15 to be connected to the reach rod, arms adapted to straddle the front axle assembly, and means carried by the upper arm of the yoke and adapted to rockably support a bolster thereon.

20 4. A running gear for wagons having a metal yoke including a body portion adapted to be connected to the reach rod, arms adapted to straddle the front axle assembly, and braces connected to the upper arm of the 25 yoke and adapted to be connected to a bolster.

5. A running gear for wagons having a metal yoke including a body portion adapted to be connected to the reach rod, arms adapted 30 to straddle the front axle assembly, and braces connected to the upper arm of the yoke and adapted to be connected to a bolster, one of said braces being of V-shaped form.

35 6. A running gear for wagons having a metal yoke including a body portion adapted to be connected to the reach rod, arms adapted to straddle the front axle assembly, braces, bolts for fastening the braces to the yoke, the braces having bolt holes slightly 40 larger than the bolts to permit relative movement of the braces relative to the yoke, said braces being adapted to be attached to a bolster.

45 7. A running gear for wagons having a front axle assembly, and an annular plate connected with said assembly and constituting the lower element of a fifth wheel, a yoke adapted to be connected to the reach and having a pair of arms, the lower arm extending below the axle assembly and the upper arm engaging the annular plate and constituting the upper element of the fifth wheel, and means for pivotally connecting the yoke with the axle assembly.

55 8. A running gear for wagons having a front axle assembly, an annular plate connected with said assembly and constituting the lower element of a fifth wheel, a yoke adapted to be connected to the reach and having a pair of arms, the lower arm extending below the axle assembly and the upper arm engaging the annular plate and constituting the upper element of the fifth wheel, the upper arm of the yoke being enlarged,

and means for pivotally connecting the yoke with the axle assembly.

9. A running gear for wagons comprising a front axle assembly, a fifth wheel connected thereto, a yoke adapted to be connected to a reach and having forwardly extending arms, the lower arm underlying the axle assembly, the upper arm overlying the fifth wheel, a bolster positioned on said upper arm, means for pivotally interconnecting the bolster, yoke and axle assembly, and means for interconnecting the bolster and upper arm and for exerting a mutual bracing action on the same.

10. A running gear for wagons including 80 a front axle assembly, a fifth wheel arrangement connected thereto, and a reach rod and comprising a yoke, a pivotal connection between the rear end of the yoke and the reach rod, the forward end of the lower arm of the yoke engaging the underside of the front axle assembly, the forward end of the upper arm of the yoke engaging the upper side of the fifth wheel arrangement, a bolster resting on the upper arm of the yoke, means 85 for pivotally interconnecting the bolster yoke and front axle assembly, and braces between the bolster and the upper arm of the yoke.

11. A running gear for wagons including 90 a front axle assembly, a fifth wheel arrangement connected thereto, and a reach rod and comprising a yoke, a connection between the rear end of the yoke and the reach rod, the forward end of the lower arm of the yoke 95 engaging the underside of the front axle assembly, the forward end of the upper arm of the yoke engaging the upper side of the fifth wheel arrangement, a bolster resting on the upper arm of the yoke, means for pivotally interconnecting the bolster yoke and front axle assembly, and braces between the bolster and the upper arm of the yoke.

12. A running gear for wagons including 100 a front axle assembly, a fifth wheel arrangement connected thereto, a reach rod and comprising a yoke, a connection between the rear end of the yoke and the reach rod, the forward end of the lower arm of the yoke 105 engaging the underside of the front axle assembly, the forward end of the upper arm of the yoke engaging the upper side of the fifth wheel arrangement, a bolster resting on the upper arm of the yoke, means for pivotally interconnecting the bolster yoke and front axle assembly, and braces between the bolster and the upper arm of the yoke.

13. A running gear for wagons including 115 a front axle assembly, a fifth wheel arrangement connected thereto, a reach rod and comprising a yoke, a connection between the 120 upper arm of the yoke and the upper arm of the yoke, certain of said braces engaging the upper arm of the yoke at points which overlie the surfaces of the upper arm of the yoke engaged with the fifth wheel arrangement.

4
1 rear end of the yoke and the reach rod, the forward end of the lower arm of the yoke engaging the underside of the front axle assembly, the forward end of the upper arm 5 of the yoke engaging the upper side of the fifth wheel arrangement, a bolster resting on the upper arm of the yoke, means for pivotally interconnecting the bolster yoke and front axle assembly, braces between the 10 bolster and the upper arm of the yoke, the braces having connections with the yoke permitting relative movement to permit of limited rocking of the bolster.

14. A running gear for wagons including 15 a metal yoke having a body portion and forwardly directed arms, a pivotal connection between the body portion and the reach, the forward ends of the arms being adapted to be connected with the front axle assembly 20 of the wagon, and means for bracing the

arms to maintain them in proper relation and to prevent distortion of the body portion.

15. A running gear for wagons including 25 a metal yoke having a body portion and forwardly directed arms, a pivotal connection between the body portion and the reach, the forward ends of the arms being adapted to be connected with the front axle assembly 30 of the wagon, means for bracing the arms to maintain them in proper relation and to prevent distortion of the body portion and including a brace bar extending between the arms, bolts interconnected with the arms and with the brace bar, and sleeves mounted on the bolts and connected with the brace bar to hold the brace bar in position and to supplement its bracing action on the arms. 35

FRANK MARION KENNEDY.
